UNITED STATES PATENT OFFICE.

HARVEY HUESTIS, OF PROVIDENCE, RHODE ISLAND, ASSIGNOR TO HUTCHISON & HUESTIS, OF SAME PLACE.

DESIGN FOR A SETTING FOR JEWELRY.

SPECIFICATION forming part of Design No. 14,157, dated August 7, 1883.

Application filed April 23, 1883. Term of patent 7 years.

To all whom it may concern:

Be it known that I, HARVEY HUESTIS, residing at Providence, in the county of Providence and State of Rhode Island, have invented and 5 produced a new and original Design for Settings for Jewelry; and I hereby declare that the following is a full, clear, and exact description of the same, reference being had to the accompanying drawings, forming part of this 10 specification.

Figure 1 is a perspective view of a ring provided with my newly-designed setting for jewelry. Fig. 2 is a plan view of my newly-designed setting, and Fig. 3 is a plan view of a 15 modification of the same.

Jewelry settings have heretofore been made so as to form a plain, chased, or beveled border, from which clamps projected to secure the jewel. In all such cases the border was of uniform 20 height around the jewel.

The leading feature of my design consists of a frame having a number of square blocks on each of the sides of the jewel, and corners which are beveled, so that the square blocks 25 stand out prominently.

In the drawings, *a* is the jewel.

bb are square or oblong blocks, divided from each other by a cut or line.

c c are the beveled corners, which, by reason 30 of the beveled surface, recede below the surface of the blocks. These corners may be rounded, as is shown in Fig. 3, and the facets *dd* may be cut into the corners, as shown in Fig. 3, or they may be left plain, as shown in Figs. 35 1 and 2. As the bevel of the corners clearly

defines and separates the blocks from the corners, they appear to the eyes clear and distinct, presenting an agreeable and massive appearance and enhancing the beauty and outline of the stone or jewel. The inner surface of the 40 blocks and corners may be at the same height; but I prefer to have the blocks slightly project above the inner edge of the beveled corners, so as to still more prominently present the blocks.

45

My newly-designed setting can be used for rings, charms, pins, ear-rings, and other jewelry in which a jewel or stone is set.

Having thus described my invention, I claim as new and desire to secure by Letters Patent— 50

1. The design for jewelry setting herein shown and described, the same consisting of a number of the blocks *bb* and the beveled corners *cc*, as described.

2. The design for jewelry setting herein 55 shown and described, the same consisting of a border surrounding the jewel, divided into square blocks on each of the sides of the jewel and beveled corners.

3. The design for jewelry setting herein 60 shown and described, the same consisting of a border surrounding the jewel or stone, having a group of square blocks separated by a beveled space, so as to give prominence to the blocks, as described.

HARVEY HUESTIS.
